UNITED STATES PATENT OFFICE.

CONRAD T. HANSEN, OF DETROIT, MICHIGAN, ASSIGNOR TO THE AMERICAN MOTOR BODY CORPORATION, OF PHILADELPHIA, PENNSYLVANIA, A CORPORATION OF DELAWARE.

WINDOW STOP.

Application filed November 21, 1923. Serial No. 675,985.

This invention relates to window stops, and more particularly relates to window stops which are suitable for use in glass wells in the doors and bodies of closed automobiles.

Heretofore it has been customary to limit downward movement of the window glass in closed automobile bodies and the like by fastening cross bars or wooden blocks in the glass wells at a particular place therein. Such stop members are not intended to be removed. If these stop members are supplied with rubber bumpers, neither the stop nor the bumpers may be replaced on account of the permanent attachment of the bumpers to the stop and the permanent attachment of the stop in the well.

The principal aim of my invention is to provide a window stop which may quickly and easily be mounted in a glass well in adjusted position without requiring the glass runway to be cut or mutilated. Another object of my invention is to provide a window stop having a rubber bumper which may readily and easily be attached to or detached from the stop, thereby permitting renewal and replacement of the bumper element. A further object of my invention is to provide a window stop which may be painted or enameled before being mounted in the glass well. A further object of my invention is to provide a window stop of the character described which is simple, durable and inexpensive in construction, and one which may readily and easily be attached to and be detached from a glass well. Other objects of this invention will be in part obvious and in part pointed out hereinafter.

In order that a clearer understanding of my invention may be had, attention is hereby directed to the accompanying drawings forming a part of this application and illustrating one possible embodiment of my invention. Referring to the drawings, Fig. 1 is a side view of a fragment of window runway mounted on a frame member, and a window stop and bumper embodying my invention associated therewith, the view being taken on the line 1-1 of Fig. 3; Fig. 2 is a horizontal sectional view of the same and is taken on the line 2-2 of Fig. 1; Fig. 3 is a vertical sectional view of the same and is taken on the line 3-3 of Fig. 1; Fig. 4 is a perspective view of the window stop without the bumper element; and Fig. 5 is a

perspective view of the bumper element of the window stop. Similar reference characters refer to similar parts throughout the several views of the drawings.

Referring to the drawings, there is shown, 60 somewhat diagrammatically, a frame member 1 carrying a vertical, channel shaped window runway 2 of usual construction. The frame member 1 and runway 2 form one side of the glass well, and there is a similar construction at the opposite side of the well. 65

My improved window stop comprises a bifurcated member 3, preferably of metal, adapted, when in horizontal position, to 70 straddle the runway 2, and having flange portions 4 which are adapted to come against the frame member 1 on each side of the runway 2, permitting the stop member 3 to be secured to the frame member 1 over the glass well 2 at any desired height by means of ordinary screws 5 placed through suitable perforations 6 provided therefor in the flanges 4 and screwed into engagement with the frame member 1. The stop member 3 is provided preferably with a groove 7 bounded by shoulders 8, permitting a bumper member 9 of suitable material, such as rubber, to be detachably associated with the stop. To this end the bumper member 9 is 75 provided with lateral grooves 10 adapted to receive the shoulders 8. When the window 11 is lowered, its bottom edge 12 will contact the top of the bumper 9, and is thus prevented from lowering further. 80 85 90

The stop member 3 is preferably painted or enameled before a bumper 9 is associated therewith, and also before the stop is mounted in a glass well. In practice, a stop member is located over each of the two opposite 95 runways in a glass well. The stops may be mounted at any desired height in the well and do not require the cutting away or mutilating of the runways. When a bumper 9 is worn out or requires replacement, this may 100 be readily accomplished.

As many changes could be made in the above construction and as many apparently widely different embodiments of this invention could be made without departing from 105 the scope thereof, it is intended that all matter contained in the above description or shown in the accompanying drawings shall be interpreted as illustrative and not in a limiting sense. 110

What I claim is:—

1. In combination, a window stop member having a U-shaped portion constituting at the base of the U a seat for a bumper element, the ends of said U-shaped portion being bent at an angle to the plane of the U and constituting attachment flanges, and a bumper element on the said seat, said bumper element having grooves and slidably interlocking with portions of the stop member seated in said grooves.
2. In combination, a window stop member having a U-shaped portion constituting at the base of the U a seat for a bumper element,

ment, the ends of said U-shaped portion being bent at an angle to the plane of the U and constituting attachment flanges, and a bumper element on the said seat, said bumper element having grooves and slidably interlocking with portions of the stop member seated in said grooves.

This specification signed this 12th day of November, 1923.

CONRAD T. HANSEN.
